[57] **CLAIM**

The ornamental design for a pocket for footwear, as shown and described.

DESCRIPTION

FIG. 1 is a front perspective view of a pocket for footwear, showing my new design;

FIG. 2 is a front elevational view thereof;

FIG. 3 is a left side elevational view thereof, the right side being a mirror image thereof;

FIG. 4 is a top plan view thereof;

FIG. 5 is a bottom plan view thereof; and,

FIG. 6 is a front perspective view thereof with the pocket open.

The broken line showing of a boot in FIG. 1 is for illustrative purposes only and forms no part of the claimed design.

1 Claim, 2 Drawing Sheets
